UNITED STATES PATENT OFFICE.

GEORG CARL HEINRICH WICHMANN AND ARTHUR BURROUGHES EVANS,
OF LEEDS, ENGLAND.

MACHINE FOR PRINTING ON TIN PLATES OR THE LIKE.

No. 823,835.

Specification of Letters Patent.

Patented June 19, 1906.

Application filed August 30, 1904. Serial No. 222,774.

To all whom it may concern:

Be it known that we, GEORG CARL HEINRICH WICHMANN, residing at 4 Ladywood road, Roundhay, Leeds, and ARTHUR BURROUGHES EVANS, residing at 13 The Terrace, Beeston Hill, Leeds, in the county of York, England, subjects of the King of Great Britain and Ireland, have invented certain new and useful Improvements in Machines for Printing on Tin-Plate or the Like, of which the following is a specification.

In tin-plate-printing machines hitherto made wherein the inked design is transferred from the stone or cylinder carrying the design to a blanket mounted on a cylinder and thence to a tin-plate passed between the last-named cylinder and another it is always necessary to stop the cylinders every time a tin-plate is inserted between them.

By our invention we construct a machine consisting of three continuously-rotating cylinders which can be brought into rolling contact with each other and withdrawn from such contact as may be necessary, one carrying the aluminium or like printing surface, the second the rubber or like blanket, and the third or backing cylinder provided with grippers arranged to open and to receive the tin-plate at the moment when the latter is allowed to fall from a substantially vertical position by removal of supports. In this machine there is no necessity to stop the cylinders so long as normal working proceeds. The operator feeds the tin plates successively on to the supports as fast as they are removed by the grippers to be drawn between the blanket-cylinder and the backing-cylinder. It follows that the output of the machine is considerably greater than that of previous machines.

In the accompanying drawings, Figure 1 is a side elevation of a machine made according to the invention. Fig. 2 is a part longitudinal section; and Fig. 3, a part front elevation, drawn to an enlarged scale, showing the feeding and gripping mechanism.

The machine comprises three revolving cylinders *a*, *b*, and *c*. Of these *c* carries a surface of aluminium or other suitable material whereon is the design to be printed, such design being damped by rollers fed with water in any known manner and intermittently applied under action of a cam on the shaft of the cylinder and being inked by other

rollers fed with ink in any known manner. 55 This cylinder, with its damping and inking devices, is well known in the so-called "rotary lithomachines," as is also the second cylinder *b*, which is arranged to revolve in contact with cylinder *c* and carries a rubber or like 60 blanket to which the design on *c* is transferred. The third cylinder *a* forms the backing or support for the sheets of tin or the like while they are receiving the design from the second cylinder and is cut away longitudinally, as at *a'*, for the reception of a shaft *d*, 65 on which is mounted a series of grippers *e*, which are adapted to close on the lower edge of the tin plate or sheet and to hold it firmly against the cylinder during printing. 70

The tin plate or other sheets are stacked on the lay-board *f*, from which they are taken one at a time and placed against the steel face plates *g* of a vertical feed-board *g'*, secured to a bracket *g''* on the machine-frame. The sheet is pushed down the face-plate until its lower edge rests on the arms or lays *h*, being guided into and held in position thereon by steel springs *i* and smoothers *k*. The steel springs *i* are preferably mounted to slide 75 transversely on a guide-bar *i'*, attached to the rear side of the face-plate for the purpose of adjusting them to various sizes of plates. The grippers *e* and smoothers *k* are also preferably mounted to be adjustable transversely 80 on their shafts for the like purpose. The grippers *e* are closed upon the upper edge of the recess *a'*, as hereinafter described, at the moment when this edge is level with the top surface of the lays *h*, so as to grip the lower 85 edge of the sheet against the cylinder, and at the same moment the lays *h* and the smoothers *k* are turned backward. As the cylinder *a* has a continuous rotary motion and the tin plates or other sheets have usually an appreciable mass, a considerable inertia has to be overcome in starting the sheets from rest to move with the cylinder, and the arrangement of guides above described giving a vertically downward feed enables the force of 90 gravity to be utilized to overcome the inertia of the plates.

The plate when seized by the grippers is carried round with the cylinders *a* inside a fixed curved guide or guides *l*, concentric 105 with the cylinder, by which it is bent to the curvature of the cylinder, and while still constrained by the curved guide is brought into

printing contact with the blanket-cylinder *b*, receiving an impression of the design. A second curved guide or guides *l'* constrains the plate until its free end reaches the delivery-tray *l''*, when the natural spring of the plate causes the free end thereof to spring outward, and the grippers being at the same time turned to release the plate, as hereinafter described, the latter falls by gravity on the delivery-tray, with the printed side upward.

The movement of the lays *h* and of the smoothers *k* is obtained from the cam *m* on the end of cylinder *a*, which engages a bowl or runner *n* on a lever *n'*, pivotally mounted on the feed-board bracket. The nose of the lever *n'* is pushed by the action of the cam against a bowl *o* on an arm *o'*, which is fixed on the shaft *h'*, to which the lays *h* are also attached. The smoothers *k* are carried by a shaft *k'*, on which also is fixed an arm *k''*, which is connected by a link with an arm *h''*, fixed on the shaft *h'*. When the cam comes into engagement with the bowl *n*, the shafts *h' k'* are rocked and the lays *h* and smoothers *k* thus retracted. When the cam disengages, the parts are returned to their original position by means of a spring which is set on the outward movement of the lays.

One end of the gripper-shaft *d* terminates in a slide or channel piece *d'*, (shown in dotted lines in Fig. 2,) which is adapted to engage with a pin *p*, attached to the main bracket, by means of which the shaft *d* and grippers *e* are turned as the shaft rotates with the cylinder into the position shown in the drawings, in which the grippers have been closed on the plate and the guide *d'* is just disengaging the pin *p*. During the engagement of the pin *p* and guide *d'* the shaft *d* will be rotated through about two right angles, since the axis of the shaft is nearer the axis of the cylinder than that of the fixed pin which enters and leaves the guide at the same end—viz., that end which it is shown in the drawings as leaving.

To keep the grippers closed or open, as the case may be, there is fixed to the shaft *d* a lever-arm *e'*, to which is pivoted a rod *e''*, passing through a slot in a hook *e''*, which is suspended on the shaft of cylinder *a*. This rod is surrounded by a compression-spring *e'*, one end of which bears against a collar *e''* on the rod, while the other end bears on the hook *e''*. It will be seen that in the position shown in full lines in Fig. 2 the spring *e'* is acting to keep the grippers closed. When the shaft *d* has been turned in the manner described below, the lever-arm *e'* and rod *e''* occupy the position shown in dotted lines, and the spring *e'* keeps the grippers open.

The grippers are released by the engagement of the guide *d'* with a second pin *p'* or a casting *p''*, which is capable of being turned round the axis of the cylinder *a* and is slotted at *p''* for the purpose of allowing such move-

ment through a suitable range and of clamping the casting in any desired position within such range. By means of this adjustment the pin *p'* can be arranged to engage the guides *d'*, so as to retract the grippers *e* when the tail end of the tin-plate or other sheet is just level with the top of the delivery-tray *l''*. The pin *p'* is nearer to the axis of the cylinder *a* than the axis of the shaft *d* is, and consequently the engagement of the pin *p'* in the guide *d'* will rotate the shaft *d* through about one hundred and eighty degrees in the reverse direction to that in which it was rotated by the engagement with the pin *p*, the grippers being thereby turned backward into the space or slot *a'* in the cylinder.

The shaft *b'* of the blanket-cylinder *b* is journaled in a bush *q*, the axis of which is eccentric to that of the shaft. The bush *q* is adapted to be rocked so as to throw the center of the shaft *b'* away from the cylinders *a* and *c* by means of an arm *q'*, which is connected by an adjustable link with a lever *r*, pivoted in the frame, another lever *r'*, mounted on the same shaft as *r*, but within the frame, being adapted to engage a catch-hook *s*, which is continually reciprocated by means of a bell-crank lever *s'*, the other end of which carries a bowl *t*, which engages in a cam-groove *t'* in the end of the cylinder *b*. The external linkage for retracting the cylinder *b* is duplicated at the other end of the cylinder.

Usually when the machine is printing the catch-hook *s*, which is supported on a bowl *u*, mounted on a lever *u'*, which is operated by a spring-returned pedal *v*, is raised, so that its forward end is clear of the lever *r'*, and the latter remains in the position in which it is shown in Fig. 1. When, however, the pedal *v* is depressed, as shown in Fig. 1, the forward end of the catch-hook drops into engagement with the lever *r'*, which is thus pushed backward and forward by the catch-hook as the cylinder *b* rotates. The movement of the lever *r'* is transmitted through the linkage described to communicate a rocking motion to the eccentric bush *q*, in which the shaft of the cylinder *b* is journaled. As a result, when the lever *r'* is pushed backward and forward the axis of the cylinder *b* is moved, so as alternately to withdraw the cylinder from printing contact with the cylinders *a* and *c* and to return it thereto. When the pedal *v* is released, it is returned by its spring to the upper position and the catch-hook *s* is raised by the bowl *t* to its inoperative position, the lever *r* being returned to the position shown in Fig. 1, in which it is held by means of a spring *r''*.

The cam-groove *t'* is designed so that the cylinders *b*, *a*, and *c* will be separated during that part of their revolutions in which there is printing contact between them.

Having thus described the nature of the said invention and the best means we know

of carrying the same into practical effect, we claim—

1. A machine for printing on tin plates comprising a cylinder, an inked design thereon, a second cylinder adapted to revolve continuously in contact with the first-named cylinder, a surface on the said second cylinder to which the design can be transferred a third cylinder adapted to revolve continuously in contact with the said second cylinder, grippers carried by the said third cylinder adapted to seize and hold the tin-plate to cause it to pass between the said second and third cylinders, and a mechanically-operated device adapted to allow the tin-plate to fall at the moment it is seized by the said grippers.
2. A machine for printing on tin plates comprising a cylinder, an inked design thereon, a second cylinder adapted to revolve continuously in contact with the first-named cylinder, a surface on the said second cylinder to which the design can be transferred, a third cylinder adapted to revolve continuously in contact with the said second cylinder, grippers carried by the said third cylinder adapted to seize and hold the tin-plate to cause it to pass between the said second and third cylinders, a mechanically-operated device adapted to allow the tin-plate to fall at the moment it is seized by the said grippers, and means whereby the said second cylinder can be caused to move out of contact with the other two.
3. In a machine for printing on tin plates wherein the tin-plate is held by grippers on a backing-cylinder and caused to pass between the said backing-cylinder and a printing-cyl-

inder, a frame, a vertical feed-board carried by the said frame, a rocking shaft, arms on the said rocking shaft adapted to receive the tin-plate as it is fed down the said feed-board, guides carried by the said feed-board and adapted to guide the tin-plate into position on the said arms, and means adapted to rock the said shaft to remove the said arms from beneath the tin-plate at the moment when the latter is seized by the said grippers.

4. In a machine for printing on tin plates wherein the tin-plate is held by grippers on a backing-cylinder and caused to pass between the said backing-cylinder and a printing-cylinder, a frame, a vertical feed-board carried by the said frame, a rocking shaft, arms on the said rocking shaft adapted to receive the tin-plate as it is fed down the said feed-board, guides carried by the said feed-board and adapted to guide the tin-plate into position on the said arms, a second rocking shaft linked to the first to operate therewith, smoothers carried by the said second shaft and means carried by the said backing-cylinder and adapted to rock the said shafts to move the said arms and smoothers away from the tin-plate at the moment when the latter is seized by the said grippers.

In testimony whereof we have signed our names to this specification in the presence of two subscribing witnesses.
